UNITED STATES PATENT OFFICE

2,513,352

DESEDIMENTIZER

Arthur A. O'Meara, Harrisburg, Pa.

Application February 5, 1946, Serial No. 645,674

4 Claims. (Cl. 259—81)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention refers to machines and more particularly to those adapted for the mixing or desedimentation of the contents of vessels.

Numerous liquid or fluid materials storable in containers are subject to sedimentation if stored so as to be relatively still and allowed to settle for a considerable length of time. During this process, which is relatively slow, other mechanical and physical processes are apt to occur which deteriorate the contents and make them wholly or partially unsuitable for their intended use. After the primary period of settling has occurred, the initial sedimentation is augmented by more sedimentation and the sediment becomes more compact. It is apt to stratify into a cake or layer, that is relatively dry and solidified, while the liquid vehicle proper becomes thin and watery. As time proceeds, the cake becomes harder and more stratified, while the liquid becomes more thin. However it has been found desirable to interrupt the process of precipitation periodically by suitable agitation. A critical settling time being determined, and the liquid mixture regularly agitated energetically within such time, to produce an intimate mixture again of liquid and ingredients; the mixture will remain in a suitable normal condition of admixture and diffusion for a further suspension period, during which it will be suitable for its designated purpose. It has been found that a most effective way of accomplishing this periodical precipitation, is derived by the single simple inversion of the container within the critical period and preferably facilitated by a sharp jolt.

The inversion of the package starts the process of desedimentation theoretically, but actually the molecules go through a type of Brownian movement or molecular diffusion. The solid ingredient molecules generally follow indefinite and erratic lines of travel as they bump, attract, repel and otherwise motivate around in vehicular space. The only definite practical idea of its eventual effect is obtained from the proximate established critical period of settlement, empirically derived, and the basis given by a recently proposed physical formula of the kinetic theory of molecules. This variably depends to a certain extent on the quantity of material involved, temperature, its depth and some other mechanical values of its volume. For milk, the period is just about 30 days, so inversion after 20 days is at present, considered satisfactory. The periods are usually de-

2

termined empirically according to the conditions involved, and the particular materials in the containers given the inversion or turn-over action to suit. The results sought by such turn-over are: a desedimentation, reduced deterioration, a more harmoniously mixed product, expeditious manipulation and avoidance of wastage and mechanical injury. In previous methods, this was not obtainable in a practical way and enormous financial losses were incurred.

In a particular method employed for desedimentation of liquid paints, inverting milk, and creating other mechanical liquid disturbances of the contents of vessels, it has heretofore been customary to physically lift the containers individually and then upset or shake them so that the sediment or colloidal deposit will detach and leave the bottom to mix through the liquid itself again, and again go into suspension, which it can do for a definite period of time, critical for each material. In the case of milk, as already stated, the contents should be inverted once every 20 days. Paints and other sedimentizing liquids may require longer or shorter periods depending on their individual physical characteristics.

The prior method, performed by hand, is laborious, tedious, and time-taking. It has the disadvantage that it does not do such a good job of rediffusion as the materials require.

It is an object of the invention to provide a new and improved desedimentizing machine for containers holding liquids that will avoid one or more of the disadvantages and limitations of the prior art.

An additional object of this invention is to provide a new and improved desedimentizing machine that will be capable of effectively handling simultaneously a large number of containers or cases containing the containers and holding them securely while they are being turned.

Another object of the present invention is to provide a new and improved mixing machine that will be suitable for use with pallets and pallet trucks; which will do the work expeditiously and require a minimum amount of handling.

For a better understanding of this invention and for other objects thereof, reference is made to the appended drawings and the following description, in which an example of this invention is illustrated, while the scope of the invention is particularly pointed out in the claims:

In the drawings:

Figure 1 represents a side elevation of a mixing machine employing this invention,

Figure 2 is an end view of Figure 1, and

Figure 3 is a detail of the mechanism used for

holding and disconnecting the pallets from the mixing machine.

Fig. 4 is a schematic diagram of one possible conventional switch circuit.

Similar reference characters refer to similar parts throughout the drawings.

In the particular form of construction shown in the drawings, a rotating frame 10 consists of an open spider structure, having peripheral circular, coaxial rims 11 spaced horizontally apart and carrying a truss-work 12 by which a rectangular box 13 is fixed symmetrically within the rims. The box is open on both sides of the frame and of such size as to receive horizontal pallets 14 and 15, shown respectively at bottom and top. The pallets, open at two sides, fit easily in the box and can be set in or removed by the tongues of a familiar pallet elevation truck in a conventional manner. A claw mechanism at top and bottom of the box 13 on each side includes a shaft 16 having radial operating crank arms 16' at its extremity to operate L-shaped claws 17 fixed and spaced appropriately on the shaft. The claws engage within open sides of the two pallets at one position of the shafts and prevent pallet movement in the box as the pallets move through the upper parts of their travel with the box.

At the lower horizontal or loading position only, the pallet is disengaged automatically by the claws 17 so it can be readily removed by the jack tongues of a conventional elevation truck. A torsion spring 18 engaged with the shaft 16 and anchored to the box (Fig. 3), tends to keep the claws in the engaging position when not mechanically moved by an operating arm 19, of which there is one for each of two shafts 16 at each end of the machine and two like arms. This arm 19 is installed on a standard 19' erected on a truck base 20 having elevated side strings 20' forming the general support for the frame 10. Each arm 19 is in the line of downward travel of a respective crank 16' fixed on the shaft 16, and so engages and rotates the latter in a direction counter to the action of the spring 18, swinging the claws clear of the pallet. The spider moves in half-revolutions and automatically reverses likewise after each half turn by manual switching. This is arranged for by a wiper or presser 22 acting against a plunger of a switch 23 (both formally illustrated) that throws power off the driving motor 24, and by two pairs of buffers or chocks 25 on the rims 11. One pair of buffers come against the peripheries of respective driving rollers 26 of two pairs that support and drive the rims 11. Since the contact of the rollers 26 with the rails is frictional, no considerable mechanical stresses are involved when the buffers or chocks 25 engage, even if motor is running. The result would be simply a slipping one. It does however make the stopping places in definite and uniform locations. The rollers 26 are mounted on transverse shafts 29 journaled in the strings 20', and are driven conventionally, as, by chains 28 from the motor 24.

The truck 20 is preferably supported on wheels 27, to make it portable, and enable various adjustments to be made from time to time as desired, without requiring several individuals for the effort.

In Figure 2, the bent-in end portion of each arm 19, is shown in contact with its respective handle, that is a part of the mechanism 16 and claws 17. Normally, it is torsionally tensioned to bind against the pallet, within the box-like structure 13. When at the bottom position of the

travel of the spider, the stationary arm 19, on the rigid supporting frame of the machine, is brought into contact with the handle and arcuately moves it. The shaft 16 and claws 17 will be rotated thereby in a direction away from binding the pallet, and leaves it loosely resting on the bottom side of the box 13. The pallet may then be removed, or replaced with another.

As may be seen in Fig. 2, the cranks 16' have two principal positions, in both of which they are inclined inwardly of the planes of the rims 11, and the lengths of the shafts 16 are such that the cranks are spaced considerably outward of the rims of the spider. The springs 18 operate normally to hold the cranks extending at an angle of approximately 45 degrees across the plane of the adjacent rim and away from the respective presser 22 as in full lines at the top of Figs. 2 and 3. The operating arms 19 may be simple bars fixed on the standards 19' inwardly of the planes of respective rims 11. As these cranks approach respective rollers 26, they are pointed downwardly, and extend inwardly of the operating arms 19. The latter being rigid and stationary, wipingly engage and cam the cranks inwardly and upwardly as the spider moves, until the cranks reach a claw-opening position somewhat more than ninety degrees from their initial position with respect to the axis of the shaft 16, as shown in full lines at the lower part of Fig. 2 and dotted at the upper part of Fig. 2, and in Fig. 3. When operation of the machine is thereafter reversed and as the cranks consequently withdraw from the arms 19, the spring 18 becomes effective to engage the claws, as before explained.

There are two of the switches 23, one at each end of the machine, each operable both manually and by two pressers 22 mounted on the spider frame, spaced apart and inverted with respect to each other intermediately of the peripherally spaced pairs of buffers 25. The pressers are so arranged that they will, in advancing downward, open a respective switch just as the adjacent pair of buffers 25 engages the adjacent rollers 26. The switches 23 are preferably of a pushbutton type and may be double pole reversing type switches thrown from a first position to the other on one operation, and then, on a successive operation moved back to the first position, and so that when the switch at one end is operated by the presser it is moved into reversing relation to the motor but in an open circuit. Manual operation of the opposite switch will then close this open circuit, causing the spider to move through another half turn, and opening the switch last manually operated.

In starting the machine with the box 13 empty, one of the shafts 16 at the front, and another at the back of the machine, will be at the lower side of the spider, and the other two shafts 16 at the top. The cranks 16' of the lower shafts will be engaged and the claws 17 held open by the operating arms 19. A pallet 15 is now laid in the bottom of the box, flush at both front and back with the ends of the box. Assuming that the cranks 16' are at the left end of the machine, the right hand switch 22 is then operated manually to start the motor. This results in the spider and box (empty except for the single pallet) being rotated half a turn clockwise until the right hand switch 23 is engaged by the advanced descending presser 22, stopping the machine with the newly placed pallet at the top of the box. In the first part of this movement the cranks 16' at the lower left side of the machine, become freed and the

spring 18 is permitted to operate the shaft 16 and claws 17 so as to engage and hold the pallet firmly against the underlying side of the box. As the spider nears completion of this clockwise half turn, the other pair of cranks 16' which were at the left upper side of the spider are advancing downwardly and they engage the right hand arms 19 and are operated to move and clear the respective claws. An elevating truck with a load of containers stacked on another pallet 14 is now driven to the front open end of the box 13, and the load deposited therein with its supporting pallet flush with the edges of the box as before. The top of the stack of containers will then be spaced several inches from the top pallet, as indicated in Fig. 1. After withdrawal of the truck, the left hand switch 23 is next manually operated by its hand button, closing the reversing circuit to the motor. As rotation counterclockwise occurs the load-carrying pallet 14 is gripped as before described, as soon as the spider has been rotated a few degrees, and as the load nears inverted position it slips abruptly downward onto the pallet 15 which was at the top at the time of loading. This communicates a slight shock to the load of containers which, together with the inversion which has occurred, initiates desedimentation, as indicated. The inverted load is then removed preferably from the opposite or rear side of the machine by an elevator truck brought into position to engage the pallet 15 which is at the moment on the bottom carrying the load of containers. This leaves the pallet 14 at the top held against the top of the box, and no pallet at the bottom. By reloading as before, and repetition of the switch operations, unloading and loading on each half turn of the spider, there is thus always a ready pallet held at the top of the opening through the box 13, and unloading and loading may occur on each half turn of the spider.

The removed load and its supporting pallet are stored away on its pallet until shipped, or until expiration of the assigned period for its desedimentation again, when it is again loaded in the desedimentizer, inverted, and restored. The whole machine may be moved on its wheels to the most convenient location for receiving the goods to be desedimentized, and to reduce the amount of travel required by the loading and unloading trucks.

While there has been described what is at present considered to be a new and improved embodiment of this invention, it will be noted that various changes and modifications may be made thereon without departing from the principles and spirit of the invention, as sought to be defined in the following claims.

What I claim is:

1. A desedimentizer comprising a skeleton circular spider frame having a rectangular box-like axial opening therethrough formed with two parallel load-carrying walls and constructed to receive slidably through at least one side of the frame on to a lower one of said walls and to hold thereon a stack comprising a pallet and plurality of containers thereon together conforming generally to said opening, the said walls including respective releasable means to hold a pallet thereagainst in the opening to define the effective clearance between said walls and the upper one spaced over such stack, a supporting roller mechanism under said spider for frictionally operating it rotatively, motor means for driving said mechanism, a second mechanism operated by the said spider in limited parts of its rotation to automati-

ically control the motor means when operating so as to limit travel of the spider to a position in its travel inverted from its starting position and means to energize said motor means at will.

2. The structure of claim 1 wherein manual means is included operable at will to initiate operation of said motor means, and said second mechanism includes a strike member fixed on and projecting from the spider, and a stationary mount having thereon a directional control device beside the path of rotation of the spider including a shift member in the path of the strike member and movable thereby when the spider is moving and closely approaching said inverted position from a loading position, effective on the motor means in one direction to a starting position for the succeeding operation of the motor means and effective in an opposite direction to cause rotation of the spider frame in a direction opposite that of said approach.

3. The structure of claim 2 including a machine stop for the motor means, operatively connected to said shift member and simultaneously operable with said directional control device, said strike member being constructed and arranged in relation to said shift device to hold the latter against return while said spider is at the respective limit of its travel.

4. A desedimentizer comprising a base, a circular drum-like frame supported peripherally for rotation in a vertical plane on the base, said drum-like frame having a transverse opening axially therethrough open to receive therein through the side of the frame a pallet and stacked packages thereon, said desedimentizer having means to grip pallets in said frame when moved from a loading position at the lower side of the frame and to automatically release the same when at the loading position, and reversible motive means on said base including supporting driving rollers transversely arranged under and frictionally engaged with the periphery of the frame, to rotate the same, manual control means to apply power to said motive means at will; the improvement comprising means on said base to automatically stop the motive means responsive to movement of the frame in either direction over an angle of 180 degrees from either of two opposite alternative loading positions of the frame, and means to control the direction of operation of said motive means independently of said manual control means comprising a movable shift device on the base at each side of the said frame adjacent its periphery and wiper means on the frame positioned to alternately engage and move the shift devices under movement of the frame in respective directions, to reverse its directional control, whereby on successive operations of said manual control means the frame will be rotated alternately in opposite directions and automatically stopped in respective loading positions.

ARTHUR A. O'MEARA.
